(57) **CLAIM**

I claim the ornamental design for a bottle, as shown and described.

DESCRIPTION

FIG. 1 is a perspective view of the bottle in accordance with my new design.

FIG. 2 is a top plan view of the bottle in FIG. 1, the bottom of the bottle forming no part of the claimed design.

FIG. 3 is a front elevational view of the bottle in FIGS. 1 and 2.

FIG. 4 is a rear elevational view of the bottle in FIGS. 1-3.

FIG. 5 is a side elevational view of the bottle in FIGS. 1-4, being taken from the left in FIG. 3; and,

FIG. 6 is a side elevational view of the bottle in FIGS. 1-5, being taken from the right in FIG. 3.

Dash-dash-dash broken lines shown in the drawings represent environmental structure and are not part of the claimed design.
